UNITED STATES PATENT OFFICE.

WILLIAM H. LOVELACE, OF DALNA, KENTUCKY.

HOLDER.

Application filed July 28, 1923. Serial No. 654,422.

To all whom it may concern:

Be it known that I, WILLIAM H. LOVELACE, a citizen of the United States, residing at Dalna, in the county of Letcher and State of Kentucky, have invented new and useful Improvements in Holders, of which the following is a specification.

This invention has reference to electric arc welding, and is particularly directed to 10 an electrode holder.

An important object is to produce a holder for this purpose which will quickly grip and likewise quickly release an electrode and thus obviate the necessity of cutting off the current as is true with the ordinary class of electrode holders when the electrode is engaged thereby or released therefrom.

A further object is to produce an electrode holder for electric arc welding in which the 20 outer end thereof is protected by an insulator to obviate the liability of damaging the holder when the end thereof is brought in contact with a surface of electric conductivity, such as is apt to occur when the welding operation takes place in close quarters.

The foregoing, and many other objects which will present themselves as the nature of the invention is better understood, may be accomplished by a construction, combination and operative association of parts 30 such as is disclosed by the drawings which accompany and which form part of this application.

In the drawings:

35 Figure 1 is a general view of the improvement.

Figure 2 is a sectional view approximately on the line 2—2 of Figure 1.

40 Figure 3 is a sectional view approximately on the line 3—3 of Figure 1.

Figure 4 is a perspective view showing the apertured block that provides the holder for the electrodes.

45 Figure 5 is a perspective view of the notched end of the slidable tubular member.

Figure 6 is a perspective view of the handle.

Referring now to the drawings in detail, the numeral 1 designates the handle portion 50 of my improvement. The handle is preferably in the nature of a hollow tube of insulating material and has on its outer end a disk-like guard 2 of similar material. Passing through the hollow handle, but secured thereto there is a metal tube 3. In one end of 55 this tube there are clamped the conductors.

The portion of the tube which projects beyond the guard has diametrically opposed elliptical openings 4 therethrough arranged adjacent to the outer end of the said tube. 60 This end of the tube is surrounded by a sleeve of insulating material 5 which is provided with elliptical openings that align with the openings 4.

In the tube 3 there is a slidable member 6. 65 The member 6 has on its inner end a disk 7 of insulating material, and contacting with this disk and a suitable stop 8 in the tube 3 there is a helical spring 9. The spring projects the member 6 toward the outer end of 70 the tube, and the outer end of the said member 6 is formed with a V-shaped notch to provide opposed angle jaws 10, and these jaws are normally forced by the spring beyond the 75 openings 4 in the tube and in the insulating sleeve.

Having one end passing through a slot in the tube, just outward of the guard 2 there is the straight end 11 of a handle. 80 The end 11 also enters a notch 12 in the slidable jaw carrying member 6. At the sides of the opening in the tube 3 through which the end 11 of the handle passes there are outstanding ears 13, the said end being pivoted between the ears, as at 14. The straight end 11 outward of the ears 13, is bent angularly and is thence continued at a curvature through an arcuate slot 15 in the guard 2. The rounded end of the handle, indicated by the numeral 16 has a covering 85 of insulating material 17.

To facilitate the arrangement of electrodes in the holder, I provide a block 18 that has on its upper face series of apertures each of a size to receive therein one end of an electrode 19. The apertures are so spaced that the outer end of the holder may be arranged over any of the electrodes to permit of the same being passed through the openings in the end of the holder. In this operation the insulated active end of the handle is gripped by the thumb of the operator to retract the slidable element 6 to bring its jaws away from the openings in the tube. When the electrode is arranged in the openings, the pressure on the handle is released, permitting the spring to force the member 6 to bring the jaws 10 to engage the electrode and force the same against the outer walls provided by the openings 4. In this manner the electrode is firmly gripped. In 110 a similar manner, the electrode is released.

The quick release of the electrode is a very desirable feature in the art to which this invention relates, as speed is an essential element in successful welding, and should the parts to be welded become cold, the metal will not properly fuse. In addition to this, it has been often found that the electrode will stick to the piece being welded and cause damage to the coils in the welder. With my quick release this will be obviated, and it is thought that the foregoing description when taken in connection with the drawings will fully set forth the construction and advantages of the improvement. It is to be stated, however, that I do not desire being restricted to the precise illustrative embodiment herein disclosed but hold myself entitled to such changes therefrom as fall within the scope of what I claim.

Having described the invention, I claim:

1. In arc welding, an electrode holder including a handle of insulating material having a guard at its outer end, a hollow member passing through and secured to the handle and to which the electric conductors are attached, said member having aligning openings adjacent to its outer end, a sleeve of insulating material surrounding the said end of the member and having openings therethrough registering with the first mentioned openings, a spring influenced jaw car-

rying element slideable through the member normally covering the openings, a handle for retracting the member against the pressure of its spring, said handle comprising a pivoted member having its active end of insulating material and which is directed toward the handle.

2. In electric arc welding, a holder for electrodes, comprising a handle of insulating material having a slotted guard of similar material at its outer end, a hollow metal member passing through and secured to the handle and to which the electric conductors are connected, said member having aligning elliptical slots adjacent to its outer end, a sleeve of insulating material having similar slots on said outer end, a slideable jaw carrying element in said member, and having an inner end of insulating material, a helical spring in the member contacting said end for moving the element to bring its jaws to cover the mentioned openings, a handle pivotally secured to the member and having an end received in a slot in the slideable element, and said handle having an outer curved end of insulating material which is received through the slot in the guard.

In testimony whereof I affix my signature.

WILLIAM H. LOVELACE.
